DESIGN FOR A ROUGE CONTAINER OR SIMILAR ARTICLE

Frank McIntosh, New York, N. Y., assignor to Lenthalic Incorporated, New York, N. Y., a corporation of New York

Application July 31, 1941, Serial No. 102,606

Term of patent 3½ years

To all whom it may concern:

Be it known that I, Frank McIntosh, a citizen of the United States, residing at New York city, in the county of New York and State of New York, have invented a new, original, and ornamental Design for a Rouge Container or Similar Article, of which the following is a specification, reference being had to the accompanying drawing, forming part thereof.

Fig. 1 is a top plan view of a rouge container or similar article showing my new design; and
Fig. 2 is a side elevational view thereof.

I claim:

The ornamental design for a rouge container or similar article, substantially as shown.

FRANK McINTOSH.
